UNITED STATES PATENT OFFICE.

HERBERT ETHERIDGE, OF WIMBLEDON PARK, ENGLAND, ASSIGNOR TO THE BAR-LOCK
TYPEWRITER COMPANY LIMITED, OF LONDON, ENGLAND.

TYPE-WRITER AND TYPE-BAR MECHANISM THEREFOR.

1,118,405.

Specification of Letters Patent. Patented Nov. 24, 1914.

Application filed May 23, 1914. Serial No. 840,474.

To all whom it may concern:

Be it known that I, HERBERT ETHERIDGE, a subject of the King of England, residing at Wimbledon Park, Surrey, England, have invented certain new and useful Improvements in Type-Writers and Type-Bar Mechanism Therefor, of which the following is a specification.

This invention is for improvements in or relating to typewriters and type-bar mechanism wherein sub-levers are employed for the type-bar mechanism and the arrangement of the parts is such that the points at which each sub-lever and its type bar are connected by a link fall in the same straight line as the point of pivoting of the sub-lever when the parts are in the inoperative position; this arrangement gives an ease of action and a dead return of the levers *i. e.* a return which is free from forward rebound.

According to the present invention each sub-lever takes the form of a bell-crank having its arms approximately at right-angles to each other; one arm being linked to the type-bar and the other arm connected to the key-lever by a link which, when the parts are in the position of rest, lies approximately at right-angles to its arm.

To render the writing easily visible, the type-bars where arranged to stand up between the platen and the operator are disposed at an angle of about 45° to the horizontal and each key-lever is pivoted at the back of the machine and is sloped downward from the point of pivoting to the link whereby it is attached to its sub-lever, said sloping part lying approximately at right-angles to the type-bar, and the inter-connecting points of the sub-lever and type-bar are arranged as already described.

The platen-carriage may have its runners tilted to accommodate the key-levers at the back of the machine and the back portion of the machine may be raised for the same purpose.

In the accompanying drawing a machine is shown in central longitudinal section, but only the parts necessary for setting forth this invention are illustrated.

50 Like letters indicate like parts in the drawing.

The type-bars A, one only of which is shown, are arranged in one or more concentric semi-circles inclosed by a semi-circular frame A₁ in the well-known manner,

but this frame is tilted over to an angle of about 45° to the horizontal and the type-bars when in the position of rest lie at about the same angle. Each type-bar is pivoted at A² and has a knee A³ to which a link B is pivoted at A⁴. Below each type-bar a sub-lever C is mounted having a long arm C¹ and a short arm C². The sub-lever is pivoted at C³ and its long arm is connected at C⁴ to the link B and its short arm at C⁵ to a link D lying at right angles to the arm C². The other end of the link D is pivoted at D¹ to a key-lever E. The key-lever is bent at E¹ so that the back-portion can extend upwardly and rearwardly from the point D¹ where the link D is pivoted, to the pivot-bar E² which receives the ends of the key-levers E and is situated at a higher level than the pivot-points A² of the lowest of the type-bars. This disposition insures vertical compactness of the machine. Each key-lever is kept in place against the pivot-bar and also brought back to its inoperative position after operation by a spring E³.

It will be seen that the pivot-points A⁴, C⁴ and C⁵ are approximately in line when the type-bar mechanism is in the inoperative position; further, the part of the key-lever E which lies between the pivot-point D¹ and the pivot bar E² lies approximately at right-angles to the type-bar A when the parts are in the inoperative position; also the link D lies approximately at right-angles to this back portion of the key-lever. Further, the arms C¹, C² of the sub-lever are about at right-angles to each other and the link B is in line with the arm C¹ and its point of connection A⁴ to the type-bar A is on a line which in the direction of the pull for producing the stroke is nearer to the pivot point A² at the start of the stroke than it is during the development of the stroke, but the point A⁴ finally comes back nearly to the same line as shown by the dotted position indicated in the drawing, and the arm C¹ and link B are then nearly at right-angles to each other. It is found that this arrangement of parts affords an easy start and gives acceleration to the type-bar during the stroke, the acceleration being greatest at the time of striking the platen.

Machines are already made in which the leverage is such as to give an easy start and an accelerated motion during the stroke, but it is believed that this particular mechanism 110

gives a more satisfactory action than has heretofore been produced. Further, the canted position of the semi-circular frame A¹ and of the type-bars therein, enables the writing to be easily seen by the operator.

The object of forming the key-levers so that they slope down from the pivot-bar E² to the point of connection with the link D, is to bring this part of the lever to a position at right-angles with the type-bar, as a better movement of the type-bars is found to result than is the case when the key-levers are horizontal and the type-bars are tilted into the position shown; this especially applies to such type-bars as are toward the ends of the semi-circular frame A¹.

It will be seen that the key-lever link D and arm C² of the sub-lever C are all in the best position for pulling at the start, but the arm C¹ is not in the best position relatively to the type-bar, but it can nevertheless swing out easily at the start without imparting such movement to the type-bar, so that an easy start is effected, and as it swings out it is brought to a position where it gets greater power over the type-bar and at the same time increases the speed of movement of the latter. The construction moreover has the further advantage common to type-bar mechanism of this type that the pivot-point A⁴ being in line with the pivot-points C⁴ and C³ the type-bar is locked back when in the inoperative position, that is to say, it is not easy to move the type-bar forward by thrust applied to the type end of the type-bar. From this it results that there is very little rebound with the type-bars as they strike the stop A^{1*} on the frame A¹ so that a dead return to the inoperative position is produced. To accommodate this type-bar mechanism it is found convenient to provide the frame of the machine with a front portion F which slopes upward from the operator and constitutes the key board part of the machine, and then from this a horizontal portion F¹ which carries the semi-circular frame A¹, and from that portion an upwardly and rearwardly sloping part wherein the platen-carriage G is mounted. The runners G¹ of the platen-carriage are preferably tilted to accommodate the back ends of the key-levers E and lie on this upwardly and rearwardly sloping part of the frame, and the back of the machine itself is extended upward and covered in by a plate H. The part H¹ corresponds to the back portion of the frame as usually provided on typewriters, and it will be seen that the plate H extends up considerably beyond this and is turned over at the top to meet the base for the runners of the platen-carriage.

What I claim as my invention and desire to secure by Letters Patent is:—

65 1. In a typewriter the combination of, a

frame, a plurality of type-bars pivoted thereon, key-levers pivoted on the frame one for each type-bar, right-angled bell-crank sub-levers one for each type-bar pivoted on the frame, links each connecting one arm of a sub-lever to a type-bar each of said links lying in a straight line with the axis of pivoting of its sub-lever when said type-bar is in its inoperative position and being connected to the type-bar at a point which is above and relatively near to the axis of pivoting of the type-bar the proportions of the parts being such that sufficient movement is permitted them to bring this point of connection of the type-bar approximately as much below the axis of pivoting at the end of the stroke as it was above the said axis at the beginning of the stroke, a second link one for each sub-lever connecting that arm of the sub-lever not engaged by the previously mentioned link to the key-lever allotted to that type-bar, this second link lying, when the type-bar is inoperative, approximately at right angles to the sub-lever arm to which it is connected, substantially as set forth.

2. In a typewriter the combination of, a frame, a plurality of type-bars pivoted thereon and so mounted that when in the inoperative position they lie with their longitudinal axes at an angle of approximately 45° to the horizontal, key-levers pivoted on the frame one for each type-bar the point of pivoting of each lever being at the back of the machine, right-angled bell-crank sub-levers one for each type-bar pivoted on the frame, links each connecting one arm of a sub-lever to a type-bar each of said links lying in a straight line with the axis of pivoting of its sub-lever when said type-bar is in its inoperative position and a second link one for each sub-lever connecting that arm of the sub-lever not engaged by the previously-mentioned link to the key-lever allotted to that type-bar, each of the said key-levers being sloped down from its own point of pivoting to the point of its connection with this link, and said sloping portion lying approximately at right angles to the link and the link itself lying, when the type-bar is inoperative, approximately at right angles to the sub-lever arm to which it is connected, substantially as set forth.

3. In a typewriter the combination of, a frame having a segmental support thereon, a plurality of type-bars pivoted on the segmental support and so mounted that when in the inoperative position they lie with their longitudinal axes at an angle of approximately 45° to the horizontal, key-levers pivoted on the frame one for each type-bar, the point of pivoting of each lever being at the back of the machine and above the pivot point of the lowest type-bar, right-angled bell-crank sub-levers one for each type-bar pivoted on the frame, links each

connecting one arm of a sub-lever to a type-bar each of said links lying in a straight line with the axis of pivoting of its sub-lever when said type-bar is in its inoperative position, and a second link one for each sub-lever connecting that arm of the sub-lever not engaged by the previously-mentioned link to the key-lever allotted to that type-bar, each of the said key-levers being sloped down from its own point of pivoting to the point of its connection with this link and said sloping portion lying approximately at right angles to the link and the link itself lying when the type-bar is inoperative approximately at right-angles to the sub-lever arm to which it is connected, substantially as set forth.

4. In a typewriter the combination of, a frame, a plurality of type-bars pivoted thereon and so mounted that when in the inoperative position they lie with their longitudinal axes at an angle of approximately 45° to the horizontal, key-levers pivoted on the frame one for each type-bar the point of pivoting of each lever being at the back of the machine, right-angled bell-crank sub-levers one for each type-bar pivoted on the frame, links each connecting one arm of a sub-lever to a type-bar each of said links lying in a straight line with the axis of pivoting of its sub-lever when said type-bar is in its inoperative position, a second link one for each sub-lever connecting that arm of the sub-lever not engaged by the previously-mentioned link to the key-lever allotted to that type-bar, each of the said key-levers being sloped down from its own point of pivoting to the point of its connection with this link and the said sloping portion lying approximately at right angles to the link and the link itself lying when the type-bar is inoperative approximately at right-angles to the sub-lever arm to which it is connected, and runners for a platen-carriage mounted above the sloping portion of the key-levers, the plane of the runners being tilted so that the whole platen-carriage is tilted forward to accommodate the pivoted ends of the key-levers, substantially as set forth.

5. In a typewriter the combination of, a frame, a plurality of type-bars pivoted thereon and so mounted that when in the inoperative position they lie with their longitudinal axes at an angle of approximately 45° to the horizontal, key-levers pivoted on the frame one for each type-bar the point of pivoting of each lever being at the back of the machine, right-angled bell-crank sub-levers one for each type-bar pivoted on the frame, links each connecting one arm of a sub-lever to a type-bar each of said links lying in a straight line with the axis of pivoting of its sub-lever when said type-bar is in its inoperative position, a second link

one for each sub-lever connecting that arm of the sub-lever not engaged by the previously-mentioned link to the key-lever allotted to that type-bar, each of the said key-levers being sloped down from its own point of pivoting to the point of its connection with this link and said sloping portion lying approximately at right angles to the link and the link itself lying when the type-bar is inoperative approximately at right-angles to the sub-lever arm to which it is connected, and a back covering-plate (H) which is raised relatively to that part of the machine which is immediately in front of it to accommodate the upwardly sloping ends of the key-levers, substantially as set forth.

6. In a typewriter the combination of, a frame, a plurality of type-bars pivoted thereon and so mounted that when in the inoperative position they lie with their longitudinal axes at an angle of approximately 45° to the horizontal, key-levers pivoted on the frame one for each type-bar the point of pivoting of each lever being at the back of the machine, right-angled bell-crank sub-levers one for each type-bar pivoted on the frame, links each connecting one arm of a sub-lever to a type-bar each of said links lying in a straight line with the axis of pivoting of its sub-lever when said type-bar is in its inoperative position, a second link one for each sub-lever connecting that arm of the sub-lever not engaged by the previously-mentioned link to the key-lever allotted to that type-bar, each of the said key-levers being sloped down from its own point of pivoting to the point of its connection with this link and said sloping portion lying approximately at right angles to the link and the link itself lying when the type-bar is inoperative approximately at right-angles to the sub-lever arm to which it is connected, and side walls to the machine which slope upward from the front to the back of the key-board and are then continued along a horizontal plane in which plane the support for the type-bars is mounted substantially as set forth.

7. In a typewriter the combination of, a frame, a plurality of type-bars pivoted thereon and so mounted that when in the inoperative position they lie with their longitudinal axes at an angle of approximately 45° to the horizontal, key-levers pivoted on the frame one for each type-bar the point of pivoting of each lever being at the back of the machine, right-angled bell-crank sub-levers one for each type-bar pivoted on the frame, links each connecting one arm of a sub-lever to a type-bar each of said links lying in a straight line with the axis of pivoting of its sub-lever when said type-bar is in its inoperative position, a second link one for each sub-lever con-

necting that arm of the sub-lever not engaged by the previously-mentioned link to the key-lever allotted to that type-bar, each of the said key-levers being sloped down. 5 from its own point of pivoting to the point of its connection with this link and said sloping portion lying approximately at right-angles to the link and the link itself lying when the type-bar is inoperative approximately at right-angles to the sub-lever arm to which it is connected, and side walls 10 to the machine which slope upward from the front to the back of the key-board and are then continued along a horizontal plane

in which plane the support for the type-bars is mounted after which it is again sloped up to provide ends for a boxing to accommodate the back ends of the key-levers and the type-carriage mounted on the plane of this last-mentioned sloping portion, substantially as set forth. 15 20

In testimony whereof I have signed my name to this specification in the presence of two subscribing witnesses.

HERBERT ETHERIDGE.
